UNITED STATES PATENT OFFICE.

ARTHUR ROBERTS, OF EVANSTON, ILLINOIS.

ART OF HEATING.

1,200,871.

Specification of Letters Patent. Patented Oct. 10, 1916.

Application filed August 5, 1915. Serial No. 43,753.

To all whom it may concern:

Be it known that I, ARTHUR ROBERTS, a citizen of the United States, residing at Evanston, county of Cook, and State of Illinois, have invented certain new and useful Improvements in the Art of Heating, of which the following is a specification.

The present invention has reference to certain improvements in the art of heating, and particularly the art of heating walls, such, for example, as coke oven walls. The discoveries herein disclosed and shown, by way of example, as being applied to a particular use are very well adapted for use in the art of coke manufacture, but it will appear that the usefulness of the invention is in nowise limited to this particular art.

The features of the present invention may be used, either in connection with the transfer of heat from the hot gases to a wall, as in the case of a coke oven heating wall, or in connection with the transfer of heat from the hot wall to the comparatively cool gas or air, as in the case of a recuperating wall; in the first case the heat is transferred to the wall by the bombardment of the hot gas against the wall, thereby extracting the heat from the hot gas and transferring it into the wall by impingement; in the second case, the air is caused to absorb heat from the wall by the bombardment of the air against the wall, thereby extracting the heat from the hot wall by the impingement of the cool air against the hotter wall. Furthermore, said principles are equally applicable for the transfer of heat between a wall and either gas or air. Hence, where in this specification and the claims to follow, I make reference to the transfer of heat from the gas or air to the wall, it will be understood that I contemplate equally a converse transfer from the wall to the gas or air; and in like manner, where I use the term "gas," it will be understood that I contemplate also "air" within the meaning of that term.

Where it is desired to effect transfer of heat between gas and a wall or other structure, such heat transfer may be accomplished by radiation, convection, or conduction. Air and gas constitute relatively poor conductors of heat, and, therefore, the transfer of heat from those layers of gas separated a substantial distance from the surface of the wall into or from the wall itself, is greatly hindered and lessened by this fact. Therefore any means or method

which tends to prevent the formation of separate layers of gas or air, which layers ordinarily travel parallel to the wall; and which means or method serves to drive all portions of the gas into intimate contact with the wall, will accelerate and increase the heat transfer between the gas and wall. If the heat is to be rapidly transferred between the gas on the one hand, and the wall or other body on the other hand, and by the term "rapid transfer," I mean the transfer of a comparatively large number of heat units per unit of area in a given time interval, then such transfer must be accomplished rather by convection than by conduction or radiation. The various portions or masses of the body of gas must be successively brought into as intimate contact as possible with the surface. By so doing, there will be an opportunity for each portion of gas to come into that condition or position where the heat transfer can be most readily accomplished.

I have discovered the fact that if a current or stream of gas be caused to travel along a flue or other relatively large passage, there will cling to the surfaces of such flue or other passage a more or less thick layer of gas, said layer remaining relatively stationary on the surface of the flue, and serving to very largely isolate or insulate the gas within the central portion of the flue from the surface to be heated. The existence or presence of this layer of inert gas may be said to be due to skin friction of the stream of gas on the surface. As previously set forth, such a layer of inert gas will act as a heat insulating layer or medium, so that it will largely and seriously interfere with the transfer of heat between the gas and the surface. For this reason, any arrangement which relies chiefly or entirely upon the use of straight flues or such like passages for carrying the gas is necessarily an inefficient arrangement, by which I mean that it is poorly adapted to the transfer of more than a very limited number of heat units per unit area. Furthermore, it is not adapted to make possible the transfer of more than a very small percentage of the heat which is theoretically transferable.

I have discovered the fact that, if the gas be driven with violence and frequency against the surface, and if the body of the gas be considerably sub-divided into various portions, so that eventually practically every

- portion of the body of gas be brought into intimate contact with the surface, a very greatly improved heat transferring action will be secured, with the result that not only 5 will the percentage of transferable heat be greatly increased, but also it will be possible to cause a much greater heat transfer per unit of area. This will mean, in the case of a wall which is being heated, that 10 a much greater percentage of the total heat of the gas can be abstracted, and, furthermore, a much higher temperature of the wall can be secured than would otherwise be possible.
- 15 In the case, for example, of a coke oven heating wall, the gases commence their heating action at what may be termed the maximum temperature, being at a point adjacent to their point of entry into the heating wall, 20 and thereafter they become cooler as they approach the point of exit, at which point they may be termed "spent" gases. If the heat transfer per unit of area and per degree of difference in temperature on the two sides 25 of the wall, is constant in all portions of the wall, it will necessarily follow that the wall will be most greatly heated adjacent to the point of entry of the gases, and the amount or extent of heating will diminish toward 30 the point of exit of the gases. The result will be that the wall will be unevenly heated, being materially hotter in some portions than in others.
- 35 I have discovered the fact that, by regulating or adjusting or modifying the amount of the impingement action of the hot gases in the different portions of the wall, increasing the impingement per unit of area toward the point of exit as compared to the 40 impingement per unit of area adjacent to the point of entry of the gases, I can secure a practically uniform amount of heat transfer per unit of area at all points within the wall being heated, so that the resulting temperature at all points of the wall will be practically the same, notwithstanding the fact that the heating gases are becoming cooler or more spent as they approach the discharge point. To accomplish this result, 45 50 I may cause the rate of impingement of the gases to increase in such ratio that the rate of percentage of absorption of heat correspondingly increases as the gases cool, thereby keeping or maintaining constant at all points the amount of heat absorbed into 55 each unit of area.
- Therefore, it may be stated that in broad terms my invention consists in causing the 60 gases to undergo an impingement action so as to prevent the formation of layers of inert gas adjacent to the surfaces being heated, and so as to ultimately insure the contact with such surface of practically each and every portion of the gas, and so as to 65 drive the gas forcibly against the surface

many times, and preferably with great frequency. In a less extended or narrower aspect, the invention consists in, furthermore, varying, or modifying the amount of impingement action per unit of area so as to compensate, in the heat transfer, for the varying temperature of the gas, and thereby secure the desired temperature at each point of the surface being heated.

Referring now to the drawings, I have 75 therein illustrated, largely as a matter of convenience, the features of my invention as applied to the art of heating a coke oven. Furthermore, the general type of coke oven construction shown in the said drawings is 80 also shown in my Letters Patent of the United States, No. 1,132,685, issued to me March 23, 1915. It will be understood, however, that the invention is in nowise limited to the heating of coke ovens, nor, for that 85 matter, to the transfer of heat from the gas to the wall or other surface, but that the features may also be used for the heating of other structures, or, for that matter, for the transfer of heat from the wall or other 90 structure to the gas or air.

In the said figures: Figure 1 shows a cross section through a coke oven construction embodying the features of the invention, there being also shown in elevation coke 95 ovens adjacent to its side portions; Fig. 2 shows a vertical section taken on the line 2—2 of Fig. 1, looking in the direction of the arrows; Fig. 3 shows a fragmentary horizontal section take on the line 3—3 of Fig. 1, looking in the direction of the arrows; Fig. 4 shows a fragmentary horizontal section taken on the line 4—4 of Fig. 1, looking in the direction of the arrows; Fig. 5 shows a fragmentary horizontal section taken on the line 5—5 of Fig. 1, looking in the direction of the arrows; Fig. 6 shows a plan view of one form of impingement block used in the construction illustrated; Fig. 7 shows a vertical elevation of the block shown 100 in Fig. 6; Fig. 8 shows a plan view of another type of impingement block, the same being adapted to cooperate with the block shown in Figs. 6 and 7; Fig. 9 shows a side elevation of the block shown in plan in Fig. 110 8. Fig. 10 shows a fragmentary section through a modified construction of a wall in which use is made of a zigzag flue, the impingement in this case being secured by the forcible striking of gases against the sides 115 of said flue.

In the arrangement illustrated, the numeral 10 designates the carbonizing chamber of the oven to which the features of the present invention have been applied. The walls 11 and 12 are the heating walls. Along the upper portion of each heating wall is a row of burners 13 which deliver the combustion mixture into the heating walls. In the arrangement illustrated, each burner de- 120 125 130

livers its combustion mixture into a short flue or individual passageway 14 in the upper portion of the heating wall. As the burning gases travel down through the passage 14, heat is abstracted from them in the usual manner, which I will term "skin friction". Commencing substantially at the line 15, the transfer of heat is by the principle of impingement. In the application of this principle, as illustrated in the drawings, I take a number of blocks and recess the side and bottom surfaces of their central portions substantially as illustrated in Figs. 6, 7, 8, and 9. The end portions of these blocks are so formed that they complement each other, and, therefore, may be set together alternately in the courses, so as to build up the wall from the two forms of block. The wall as thus constructed will be provided on its interior portion with a mesh work of communicating passages, said passages being formed by the presence of the notches or recesses in the blocks. By staggering the alternate courses of blocks, so as to make them break joints, as shown in Fig. 2, the mesh of passages will be zigzagged, as illustrated, so that gases passing down through these passages will not be able to travel by a direct course, but will be thrown repeatedly back and forth and against the blocks. Beneath each of the heating walls, I have illustrated a channel 16, wherein the spent gases are received from the entire lower edge of the heating wall. Beneath the sole is the passage 17, into which the spent gases from the passages 16 are collected by means of cross connections 18.

Referring again to Figs. 6, 7, 8, and 9, the block shown in Figs. 6 and 7 has the recesses 19 and 20 on its side portions, and the recess 21 on its bottom portion. Its ends 22 and 23 are beveled or tapered inwardly. The block shown in Figs. 8 and 9 is provided with side recesses 24 and 25, and with a bottom recess 26, and its end portions 27 and 28 are beveled or tapered outwardly. The size of the passages or openings formed within the body of the wall by the presence of the recesses will be determined by or be dependent upon the size of the various recesses. Therefore, it is only necessary to select blocks having recesses of desired size in order to secure passages of the desired size within the body of the wall.

An examination of Fig. 2 will show that, as the gases travel from the burners toward the point of exit, they are subjected to very rapid and violent contact or impingement against the blocks of the wall. The velocity of the gases will be very high, so that the impingement action will be still further increased, and the gases will be driven rapidly with great violence against a large number of blocks before they are able to reach the exit. This arrangement is to be distin-

guished from one in which the gases travel through relatively large or wide openings and between comparatively few blocks, and at comparatively low velocity, because in such an arrangement the gases simply slide past and around the various blocks without being forcibly driven against them, and without the production of a true impingement action, such as I contemplate in my invention.

I have previously explained that in its more restricted or narrower scope, my invention also consists in varying the amount of impingement action as the gases travel from the entrance to the exit, so that, as they become more and more spent or exhausted, nevertheless substantially the same number of heat units will be taken into each unit area of the wall at every point in the wall. This will secure a substantially uniform heating or temperature of the wall at all points from the entrance to the exit. With such an arrangement, the wall will necessarily be uniformly heated, and, therefore, this additional feature is of great value in those constructions where it is desired to secure a uniform transfer of heat through all portions of a wall of considerable area, as, for example, a coke oven heating wall. This varied amount of impingement action may be secured in different ways, one of which consists in varying the sizes or openings of the gas passages at various points in the wall, so that the impingement action will increase as the gases approach the point of exhaust. In the particular construction illustrated, the variation in the sizes of the passages is accomplished by varying the sizes of the recesses of the blocks. Thus, examination of Fig. 2 shows very distinctly that the passages in the upper portion of the mesh, that is, just below the line 15, are very much larger in section than those in the lower portion of the mesh, that is, just above the channel 16. While I have shown the variation of impingement action as being secured by variation of the sizes of the passages, still it is obvious that other expedients might be adapted for varying the amount of impingement at different points.

In the arrangement shown in Fig. 10, the gases travel through flues 29, each of said flues being provided with a number of very sharp bends or turns, and preferably extending in zigzag manner in the same general direction. The bends are of such frequency and sharpness that the gases are driven repeatedly and with great violence against the walls or sides of the flue, so that an impingement action is secured very similar, in many respects, to the action in the construction shown, particularly in Figs. 1 to 9, inclusive. It will also be seen from examination of Fig. 10 that, in the arrangement herein illustrated, the size of the flue diminishes in the

4
direction of gas travel so that the gases are forced to travel with increased rapidity as they approach the exit, thereby increasing the frequency and violence of the impinge-
5 ment.

As an illustration of one instance in which the features of invention herein disclosed have been applied, I will mention the following: In a given installation, the impinge-
10 ment portion of a coke oven heating wall comprises twenty-four courses of blocks measured between the course 15 and the channel 16 of Fig. 2. These twenty-four courses are divided into three zones of eight
15 courses each, the openings in the top zone being larger than those in the intermediate zone, and the openings in the intermediate zone being larger than those in the bottom zone. In normal operation, the total time
20 for hot gas to travel from the course 15 to the channel 16 is less than one-half a second, divided approximately, one-half of the time traversing the upper zone, one-third of the time traversing the intermediate zone, and
25 one-sixth of the time traversing the lower zone. It may be considered that, in the ar-
rangement illustrated in Fig. 2, there is one
30 direct impingement per course, and two in-
direct impingements per course of blocks,
35 the direct impingements being occasioned by the direct striking of the gas on the upper surface of the block, and the indirect im-
pingements being occasioned by the swing-
ing of the gas around the upper and lower
40 corners of the block. It, therefore, follows
45 that, in the illustration under consider-
ation, each particle of gas is subjected to direct im-
pingements in the upper zone at the rate of
at least 32 per second, in the intermediate
50 zone at the rate of at least 48 per second, and
in the lower zone at the rate of at least 96 per second. The indirect impingements, being twice as frequent as the figures above
55 given, are, in the upper zone, at the rate of
at least 64 per second, in the intermediate
zone at the rate of at least 96 per second, and
in the lower zone at the rate of at least 192
per second.

While I have mentioned, in the foregoing
50 example, one illustration of a construction
in which certain frequencies of impinge-
ment are secured, it will be understood that
said illustration is given only by way of ex-
ample, and is not in any sense a limitation
55 upon the meaning or definition of the term
impingement.

I wish to emphasize the fact that, while I
have herein shown and described a particu-
60 lar construction in which the features of my
invention are shown, as used for the pur-
pose of heating an oven well, still they may
be applied with equal advantage in many in-
stances for the heating of gas or air flowing
65 through a wall, and in this connection I
wish to repeat that the application of the

features of the invention to the construction
shown in the drawings is done merely by
way of illustration and for convenience in a
description and understanding of the in-
vention.

70

I claim:

1. The method of heating a coke oven wall
or the like, which consists in leading hot
gases in contact with the wall, and causing
75 said gases to impinge or contact against por-
tions of the wall repeatedly and with in-
creasing violence as the gases travel along
the wall from the entrance toward the exit,
for the purpose of increasingly eliminating
80 any tendency toward the formation of lay-
ers of inert gas on the wall to thereby se-
cure a uniform heating effect.

2. The method of heating a coke oven wall
or the like, which consists in passing hot
gases through ^{the} body of the wall, and
85 causing said gases to contact or impinge
against portions of the wall repeatedly and
with an increasing amount of violence as
the gases approach the point of exit, to
thereby increasingly eliminate any tendency
90 toward the formation of layers of inert gas
on the wall, thereby giving a uniform heating
effect.

3. The method of uniformly heating a
95 coke oven wall or the like, which consists
in passing hot gases through the body of
the wall, and causing said gases to contact
or impinge against portions of the wall re-
peatedly and with an increasing amount of
100 violence as the point of exit is approached,
to thereby secure improved heat transfer be-
tween the gases and those portions of the
wall nearer to the point of exit to thereby
give a substantially uniform heating effect
105 with gases of decreasing temperature.

4. The method of uniformly heating a
110 coke oven wall or the like, which consists
in directing hot gases adjacent to the wall,
and in causing said gases to contact or im-
pinge against portions of the wall repeat-
edly and with a varying degree of violence
115 in different portions of the wall, to thereby
give a varying heat transference in differ-
ent portions of the wall, and thereby secure
a uniform temperature in the wall, notwith-
standing the variations in temperature of
the heating gases at different points.

5. The method of uniformly heating a
120 coke oven wall or the like, which consists
in causing the gases to impinge repeatedly
and violently against portions of the wall as
the gases travel from the point of entrance
toward the point of exit, the amount of im-
pingement increasing as the point of exit is
125 approached to thereby give an increased heat
transfer in those portions of the wall nearer
to the point of exit, to thereby secure a
uniform heating effect throughout the wall.

6. The method of uniformly heating a
130 coke oven wall or the like, which consists

in causing hot gases to impinge repeatedly and violently against portions of the wall, the amount of impingement varying as the gases travel from the point of entrance 5 toward the point of exit to thereby vary the amount of heat transfer in different portions of the wall, according to the requirements.

7. The method of uniformly heating a coke oven wall with a gas of varying temperature, which consists in causing said gas to impinge against portions of the wall, the amount of impingement varying in different portions of the wall to thereby give an improved heat transference in those portions of the wall where the temperature of the gases is reduced and thus secure a uniform heating effect, notwithstanding the variation in gas temperature.

20 8. The art of transferring heat between a coke oven wall and a gas, which consists in leading the gas into contact with the wall and subjecting said gas while in contact with the wall to repeated and violent impingement with portions of the wall, the amount of impingement against different portions of the wall varying, to thereby secure a desired heating effect at different points during the travel of the gas with respect to the 25 wall.

9. The art of transferring heat between a coke oven wall and a gas, which consists in

subjecting said gas while in contact with the wall to repeated violent impingement with portions of the wall to thereby improve the 35 transfer of heat between the gas and the wall, the amount of impingement varying at different portions of the wall according to the requirements.

10. The art of transferring heat between a coke oven wall and a gas, which consists in causing the gas to impinge with violence against different portions of the wall to thereby insure a maximum heat transference between the gas and the wall, the amount of 45 impingement varying at different portions of the wall according to requirements.

11. The art of transferring heat between a coke oven wall and a gas, which consists in causing the gas to travel in contact with the wall, and in successively increasingly eliminating the tendency toward the formation of 50 a layer of inert gas on the wall.

12. The art of transferring heat between a coke oven wall and a gas, which consists in causing the gas to travel in contact with the wall, and in eliminating, in successively increasing degree in different portions of the wall, the tendency toward the formation of 55 a layer of inert gas on the wall.

ARTHUR ROBERTS.
